CLAIM

The ornamental design for a shoe sole, as shown and described.

DESCRIPTION

FIG. 1 is a bottom plan view showing my new design for a shoe sole,

FIG. 2 is a left side elevational view thereof,

FIG. 3 is a right side elevational view thereof,

FIG. 4 is a toe end elevational view thereof; and,

FIG. 5 is a heel end elevational view thereof.

The appearance of the top surface as partially shown in FIG. 4 is understood to continue across the entire top surface.
